UNITED STATES PATENT OFFICE.

JOHN P. STEPPE, OF NEW YORK, N. Y., ASSIGNOR TO S. STERNAU & CO.,
OF SAME PLACE.

DESIGN FOR A SOAP-DISH.

SPECIFICATION forming part of Design No. 32,385, dated March 27, 1900.

Application filed March 1, 1900. Serial No. 7,027. Term of patent 3½ years.

To all whom it may concern:

Be it known that I, JOHN P. STEPPE, a citizen of the United States, residing at New York, borough of Brooklyn, county of Kings, and State of New York, have invented and produced a new and original Design for a Soap-Dish, of which the following is a specification, reference being had to the accompanying drawings, forming a part thereof, and in

which—

Figure 1 shows in perspective a soap-dish having my new design applied thereto, and Fig. 2 a sectional view thereof.

The leading or characteristic feature of my design consists of a frame having wires or strips extending from one end of said frame to the other and zigzag in form, the bends or angles in the wires lying adjacent to each other and forming squares, these wires or strips forming the bottom and sides of the dish.

Referring to the drawings, A represents the frame, having the sides *a* and ends *b*.

B are wires extending from one end of the frame to the other and form the bottom and sides of the dish, said wires or strips being bent in zigzag form, the bends or angles of the wires being arranged adjacent to each other, thus forming the squares *c*.

C represents supporting-arms or brackets extending from the frame A.

Having fully described my invention, what I claim as new, and desire to secure by Letters Patent, is—

The design for a soap-dish, substantially as herein shown and described.

JOHN P. STEPPE.
